UNITED STATES PATENT OFFICE.

ALPHEUS W. ALTORFER, OF ROANOKE, ILLINOIS, ASSIGNOR TO POWER WASHING MACHINE CO., OF PEORIA, ILLINOIS, A CORPORATION OF ILLINOIS.

DRIVING MECHANISM.

1,170,792.

Specification of Letters Patent.

Patented Feb. 8, 1916.

Application filed February 24, 1913. Serial No. 750,296.

To all whom it may concern:

Be it known that I, ALPHEUS W. ALTORFER, a citizen of the United States, residing at Roanoke, in the county of Woodford and State of Illinois, have invented certain new and useful Improvements in Driving Mechanisms, of which the following is a specification.

This invention has reference to a new and improved support for a wringer mechanism and to an improved driving device for such wringer mechanism.

One of the objects of the present invention is to mount the wringer and wringer actuating mechanism on a revoluble table or support, said table or support adapted to receive and support a tub or other receptacle and said table rotatable for the purpose of moving the wringer mechanism to any desired position, either for the purpose of positioning the wringer mechanism adjacent a washing machine from which clothes may be wrung and passed to the tub or other receptacle on the table or support, or for the purpose of positioning the wringer mechanism so that clothes passed from the tub or other receptacle through the wringer may be deposited in a receiving receptacle, such as a basket or the like.

The invention consists essentially of a suitable frame support on which is revolubly mounted a table, said table being preferably manually movable and provided with rollers for the easy manipulation of said table on the support; of a wringer mechanism mounted on said table and revoluble therewith; a driving mechanism for said wringer mechanism, said driving mechanism being operable in any of the various and adjusted positions of said table and being clutch controlled for the operation of said wringer mechanism when desired and which is arranged for the operation of said wringer mechanism in reverse directions, and means for operating said wringer driving mechanism.

That my invention may be more fully understood reference is had to the accompanying drawings, in which:—

Figure 1 is an elevation of my improved wringer support and driving mechanism therefor; Fig. 2 is a plan view looking down on top of the table which has been partially broken away disclosing a part of the

wringer driving mechanism, the wringer mechanism being omitted from the drawings.

Like characters of reference denote corresponding parts throughout the figures.

1 designates a frame support being preferably circular in shape and mounted on the standards or legs 2 rising from a base 3.

4 denotes a table, being circular in shape, similar to the frame support 1 but preferably slightly larger in diameter and spaced above the frame support a suitable distance and being provided with legs 5, having the rollers 6 movable on the upper surface of said frame support.

The pivot on which the table 4 revolves includes the centrally disposed operating shaft 7 having a bearing relation at its upper end with the table 6 and having a suitable bearing at its lower end on the base 3. On said shaft 7, at or near its upper end is carried a bevel gear wheel 8 and on said shaft at or near its lower end is carried a bevel gear wheel 9. Meshing with the wheel 9 is a bevel gear wheel 10, which is on the inner end of a driving shaft 11, said driving shaft being journaled in suitable bearings mounted on the base of the machine, and arranged to be driven from any suitable source of power, such as a gasoline engine, electric motor or other power.

Mounted on the table 4 is a wringer mechanism 12. This wringer mechanism may be of any preferred construction, but preferably, having a fixed position on said table and revoluble with said table. It is to be noted that this wringer mechanism is mounted on the table off center, so that by a rotation of the table, the wringer mechanism will be moved to various positions relative to the support. The shaft 13 of one of the wringer rollers extends beyond its frame and on its outer end is carried a bevel gear wheel 14 which meshes in a bevel gear wheel 15 on the upper end of a shaft 16. The shaft 16 is shown journaled in a bearing 17 secured to the wringer frame and passing down and through the table 4 has a bearing in a bracket 18, secured to the underside of the table 4, and on the lower end of the shaft 16 is carried a bevel gear wheel 19. The wheel 19 is in meshing relation with a pair of bevel gear wheels 20 and 21, loosely carried on a cross shaft 22 having a bearing

at its inner end in a bracket 23 secured to the underside of said table 4, and said cross shaft 22 at its outer end is journaled in the bracket 18. The gear wheels 20 and 21, have 5 clutch faces 24, and adapted to be alternately moved into and out of clutch engaging relation with said clutch faces 24, is a clutch member 25 slidably keyed on said shaft 22. The shaft 22 receives its power from the shaft 7 through the gear wheel 8 and a gear wheel 26 carried on the inner end of the shaft 22 and meshing with said gear wheel 8.

The clutch 25 is under the control of the 15 operator and is adapted to be moved to a neutral position with respect to said gear wheels 20 and 21 or into clutch engaging relation with either of said wheels 20 and 21 by means of a lever 27 fulcrumed on the 20 table 4 and engaging said clutch.

The machine disclosed is designed as a portable machine and is adapted to be placed beside a washing machine, or between a washing machine and a suitable receptacle, while 25 on the table 4 of the machine may be placed a tub containing rinse water, or a receptacle of any kind. When the machine is so placed and if a tub is supported on the table containing rinse water, it is obvious that if the 30 table 4 is swung around to position the wringer alongside the washing machine and the clutch gearing properly actuated, clothes passed from the washing machine through the wringer will be deposited into the tub of 35 rinse water. The clothes being sufficiently rinsed, the table 4 is swung, moving the wringer from adjacent the washing machine to a position adjacent a suitable receptacle, when the operator, if he has not already 40 done so, will reverse his operating mechanism for the wringer, so that clothes may be wrung from the rinse water into such receptacle. By the means shown, the clutch gearing may be easily and quickly reversed or 45 thrown into a neutral position and said gearing may be operated in any of the various positions of the table.

What I claim is:—

1. In a device of the character described, 50 in combination, a support, a table revolvably mounted on said support, a wringer mechanism mounted on said table off center, gearing for operating said wringer mechanism, said gearing mounted to be revolved with 55 said table, driving means for said gearing, and a clutch for controlling the connection of said gearing with said driving means.

2. In a device of the character described, 60 in combination, a support, a vertical shaft disposed centrally of said support, a table revolvably mounted on said support, the pivot of said table being coincident with the axis of said shaft, a wringer mechanism mounted on said table off center, and clutch controlled 65 means for operating said wringer mecha-

nism, said clutch controlled means being movable with said table to operate said wringer mechanism in various positions.

3. In a device of the character described, 70 in combination, a support, a vertical shaft disposed centrally of said support, a table revolvably mounted on said support, the pivot of said table being coincident with the axis of said shaft, means for transmitting power to said shaft, a wringer mechanism mounted on said table off center, gearing for operating 75 said wringer mechanism, said gearing being movable with said table and said mechanism, for operating the latter in adjusted positions, and means for actuating said gear- 80 ing from said vertical shaft.

4. In a device of the character described, 85 in combination, a support including a bed-plate, a shaft extending upwardly from said bed-plate, a table revolvably mounted at the upper end of said shaft, rollers connected with said table and presenting bearing means for the table on the bed-plate, a wringer mechanism mounted on said table off center, and means movable with the table for operating 90 said wringer mechanism.

5. In a device of the character described, 95 in combination, a support including a bed-plate, a shaft, a table revolvably mounted on the upper end of said shaft, said table having rollers movable on the upper surface of said bed-plate, a wringer mechanism mounted on said table off center and movable therewith, means for transmitting power to said shaft, a cross-shaft and means for operating 100 said cross-shaft from said first mentioned shaft, and clutch controlled gearing between said cross-shaft and said wringer mechanism.

6. In a device of the character described, 105 in combination, a table and a wringer mechanism off center thereon, both said table and said wringer mechanism being adapted to be revolved about a common pivotal point, and a driving means for said wringer mechanism, 110 said driving means being adapted to be moved simultaneously with the movement of said table and said wringer mechanism, to position said driving means to operate said wringer mechanism in any of its adjusted 115 positions.

7. In a device of the character described, 120 in combination, a suitable support, a circular table pivotally mounted on said support, a wringer mechanism having a fixed relation with respect to said table, off center 125 thereon and adapted to be moved to various positions by rotating said table, a vertically disposed shaft geared to said wringer mechanism, a driving shaft, clutch controlled gearing for operating said vertical shaft from said driving shaft, and a lever controlling said clutch.

8. In a device of the character described, 130 in combination, a base, a bed plate sup-

- ported on said base, a vertically disposed shaft, a table revoluble on the upper end of said shaft, means for transmitting motion to said shaft, a wringer mechanism mounted 5 to be revolved with said table and supported off center thereon, a vertical shaft geared to said wringer mechanism, a cross-shaft between said first mentioned shaft and said shaft geared to said wringer mechanism, clutch controlled means for controlling the transmission of power between said two last mentioned shafts, and means for controlling said clutch.
9. In a device of the character described, 15 in combination, a support, a table revoluble on said support, a wringer mechanism mounted on said table off center, a vertical shaft geared to said wringer mechanism, a second shaft for transmitting motion to said first mentioned shaft, a bevel gear wheel secured on said first mentioned shaft, a pair of bevel gear wheels loosely carried on said second shaft and in mesh with said first mentioned gear wheel, a clutch 20 25 slidably carried on said second mentioned shaft and between said pair of wheels thereon and adapted to alternately connect said wheels with said shaft, and a lever for controlling said clutch.
- 30 10. In a device of the character described, and in combination, a support, a table revoluble on said support, a wringer mechanism mounted on said table off center, whereby when said table is revolved, the 35 wringer mechanism is moved to various positions relative to the support, gearing for operating said wringer mechanism, said gearing attached to and adapted to be moved with said table, driving means for said 40 gearing, and clutch mechanism for controlling the operative connection between said gearing and said driving means.
11. In a device of the character described and in combination, a support, a table revoluble on said support, a wringer mechanism mounted on said table off center, whereby said wringer mechanism is moved to various positions relative to said support when said table is revolved, a vertical shaft 50 geared to said wringer mechanism and mounted on said table, and having a bevel gear at its lower end, a second shaft extending horizontally and mounted beneath said table having a pair of bevel gear wheels 55 loosely carried on one end in mesh with said first mentioned gear wheel, a clutch member slidably carried on said second mentioned shaft between said pair of bevel gear
- wheels adapted to connect either of said bevel gear wheels in operative relation with 60 said second mentioned shaft, a lever for moving said clutch member, and means for driving said second mentioned shaft.
12. In a device of the character described, 65 in combination, a wringer support, comprising a rotatable platform or table adapted to sustain a rinse water receptacle or the like, a wringer mechanism arranged in an upstanding position and off center on said platform or table, a vertically disposed 70 shaft, gearing between said shaft and one of the wringer rollers, and means for operating said shaft in any position of the platform or table.
13. In a device of the character described, 75 in combination, a wringer support, comprising a rotatable platform or table adapted to sustain a rinse water receptacle or the like, a wringer mechanism arranged in an upstanding position and off center on said 80 platform or table, a vertically disposed shaft, gearing between said shaft and one of the wringer rollers, a driving shaft, means for actuating the vertical shaft from said driving shaft, said actuating means being so arranged that a driving relation is 85 always maintained between the vertical and driving shafts, regardless of the position of said platform or table.
14. In a device of the character described, 90 in combination, a circular platform or table, a support on which said platform or table is rotatably mounted, a wringer mechanism supported upon said platform or table, a vertically disposed shaft geared to 95 said wringer mechanism, and means for operating said shaft in any position of the platform or table.
15. In a device of the character described, 100 in combination, a wringer and receptacle support, comprising a rotatable platform or table, a wringer mechanism arranged in an upstanding position and off center on said platform or table, a vertically disposed 105 shaft geared to one of the rollers of said wringer mechanism, a driving shaft, a cross-shaft geared to said driving shaft and clutch controlled gearing between the cross-shaft and said vertical shaft.
- In testimony whereof I affix my signature 110 in presence of two witnesses.
